UNITED STATES PATENT OFFICE

OLIVER B. MCCLINTOCK, OF MINNEAPOLIS, MINNESOTA

VAULT VENTILATOR

Application filed December 16, 1927. Serial No. 240,428.

My invention relates to bank vaults and like enclosures, and provides an extremely simple and highly efficient vault ventilator therefor. As is well known, bank vaults are 5 very solid and rigid structures, usually equipped with vault-protecting systems and rendered substantially immune to successful attack by drills, by metal-cutting torches and by flames. Otherwise, such vaults are made 10 burglar-proof and fireproof, and they are necessarily made substantially air-tight when the vault doors are closed. To afford ventilation or fresh air supply, such as will sustain life within the vault of persons either 15 accidentally locked within the vault or forced and locked within the vault by robbers, certain devices, usually called vault ventilators, have hitherto been provided, and it is to the improvement of these vault ventilators that 20 my present invention is directed. In vault ventilators hitherto proposed, it has been the universal practice, so far as I am aware, to provide screw-threaded engagement between the relatively fixed and movable members of 25 the ventilator. Such threaded engagement requires rotation and, in fact, a large number of rotations, to disconnect the removable member from the fixed member of the vault ventilator, and which action is necessary to 30 afford fresh air supply or ventilation to the interior of the vault. My invention simplifies this construction and the operation incident thereto and, at the same time, provides a ventilator-locking means that is highly ef- 35 ficient in preventing tampering with the ventilator from the exterior of the vault.

The invention is illustrated in the accompanying drawings, wherein like characters indicate like parts throughout the several 40 views.

Referring to the drawings:

Fig. 1 is a view chiefly in vertical axial section, but with some parts broken away and some parts in full, illustrating the im- 45 proved vault ventilator applied in the wall of the vault; and

Fig. 2 is a section taken on the line 2—2 of Fig. 1.

The vault wall 3 illustrated is of the usual 50 construction and may be assumed to be of

concrete. The inner face of the wall is indicated at *a* and the outer face thereof at *b*. Extended through and solidly set in this concrete wall is a tubular casing or sleeve-like shell, which may be of any suitable construction, so far as the present invention is concerned, but which, as shown, is made up of two sections 4 having flanged imbedded ends between which are interposed an insulating material 5, the said flanged ends being 55 clamped together by machine screws 6. The outer end of the outer section 4 is shown as provided with an outstanding flange that resists inward force. Of course, the out-turned flanges anchored in the concrete also 60 firmly anchor the complete sleeve-like shell against movement in either direction. The inner end of the inner section 4 projects into 65 the vault.

Normally, the opening through the anchored shell is closed by a plug that may take various forms but which, as shown, is made up of two hollow cylindrical sections 7, between the abutting ends of which is interposed a heat-insulating material 8, the said 70 two sections being rigidly connected by machine screws 9. The insulating materials 5 and 8, above described, are for reducing to a minimum the transmission of heat from the exterior to the interior of the vault in case of 75 external fire, but they constitute no part of the present invention. As shown, the interior of the outer plug section 7 is filled with concrete 10 or other fire and drill-resisting material. The outer end of said outer section 7 is preferably normally positioned approximately flush with the outer end of the outer section 4 of the casing. The inner end of the inner section of the plug 7 preferably 80 projects slightly farther into the vault than does the inner end of the inner case section 4; and to the inner end of the inner section of said plug 7 is rigidly secured a head 11 equipped with handles or hand pieces 12, preferably at diametrically opposite points. 85 Also, this head 11 is preferably formed with an annular flange 13 that loosely telescopes over the projecting inner end of the anchored shell. The head 11 is a permanent 90 part of the removable plug and may be se- 95 100

cured to the body thereof in any suitable way, but, as shown, this is accomplished by machine screws 14.

For securely and directly locking the removable plug to the anchored shell, I provide a lock that is preferably in the form of a straight coupling pin 15 inserted through coincident perforations formed in the upper and lower portions of the projecting ends of the shell and plug, as clearly shown in Fig. 1. This coupling pin 15 is provided with a shoulder 16 that limits its downward movement through the shell and plug.

Obviously, when the pin is in the position shown in Fig. 1, it will be impossible, by any force practically available, to press the plug inward by application of force to its outer end. The shearing strain of the pin 15 will be so great that the most efficient kind of a lock is provided. If, at any time, a person should be locked in the vault, it is only necessary for them to lift the coupling pin 15 out of position and then, by taking hold of the handles 12, to pull the entire plug into the vault, thereby opening the ample ventilating air passage through the anchored shell. This opening of the ventilator is accomplished without requiring rotation or any slow movements of any of the parts. When the plug is released, it may be removed by a simple straight-line movement, and this, of course, can be quickly accomplished. Aside from its extreme simplicity of operation and high efficiency, the lock feature of the ventilator is of minimum cost, has no parts that can get out of order, and the instructions for its operation from the interior of the vault will be quickly understood. For illustration, the instructions could be simply: "A: Lift lock pin out of position. B: Take hold of handles and pull plug into the vault."

While, in the best form of this ventilator, both the anchored shell and the removable plug will be made cylindrical or round in cross section, nevertheless, they both might take other forms, such as rectangular, hexagonal or octagonal forms, inasmuch as neither the plug nor any other part of the device requires rotation, either for application or removal.

What I claim is:

1. A vault ventilator comprising a tubular shell adapted to be anchored in a vault wall with one end projecting into the vault, a plug axially slidible through the entire length of said shell with its inner end projecting into the vault, and a removable coupling pin passed through the inwardly projecting end portions of said shell and plug and normally holding the parts together.

2. A vault ventilator comprising a tubular shell adapted to be anchored in a vault wall with one end projecting into the vault, a plug axially slidible through the entire length of said shell with its inner end projecting into

the vault, and a removable coupling pin passed through the inwardly projecting end portions of said shell and plug and normally holding the parts together, said plug at its inner end having a handle-equipped head.

In testimony whereof I affix my signature.

OLIVER B. MCCLINTOCK.
